TREATMENT OF HYDROCARBON OILS

Filed Nov. 9, 1933

UNITED STATES PATENT OFFICE

2,103,977

TREATMENT OF HYDROCARBON OILS

George Armistead, Jr., Scarsdale, N. Y., assignor
to Gasoline Products Company, Inc., New-
ark, N. J., a corporation of Delaware

Application November 9, 1933, Serial No. 697,272.

9 Claims. (Cl. 196—48)

This invention relates to the treatment of hydrocarbon oils, and has particular reference to a treatment in which the oil is ultimately converted into products consisting principally of gasoline and a solid or semi-solid residue such as coke or pitch. The invention is especially applicable to processes in which hot vaporous products from the cracking zone are subjected to fractionation in a plurality of independent zones in which progressively lighter fractions are condensed and removed from the cracked vapors and in which the intermediate cleaner fraction or fractions such as gas oil and kerosene, having minimum tendency to coke, is used to make up the cracking stock which is passed through the cracking zone.

In such processes, in some instances, it has been a practice to subject the heavier condensed fraction, from the initial fractionating zone, to a coking operation in which the condensate is converted into vaporized products and a solid or semisolid residue of coke or pitch.

It has also been the practice in some instances to utilize the initial fractionating zone or zones for topping or stripping fresh preheated oil of its lighter constituents in which case the residual products withdrawn from the initial fractionating zone contain the topped or reduced crude from the stripping operation as well as the initial condensate from the cracked vapors.

These residual and condensate products from the initial fractionating zone contain substantial quantities of coke and coke-forming constituents such as tarry material and polymerized material from the cracking operation which render these products unsuitable for high temperature treatment in tubular heating systems. Consequently it has been a practice to perform the coking operation in a coking zone in which the heat necessary to effect the coking is obtained by contacting the products to be coked with hot products from the cracking zone. It will be manifest that in such procedure the products subjected to the cracking operation must be given sufficient heat not only to attain the desired cracking temperatures but must be supplied with sufficient additional heat units to maintain the coking drum at the desired coking temperature.

It has been discovered that the products withdrawn from the initial fractionating zone ordinarily contain substantial quantities of constituents which if separated from the coke or coking material are suitable for treatment in tubular heating systems and that some of these constitu-

ents may even undergo severe cracking treatment.

One of the salient objects of the present invention is to reduce the proportionate amount of residual material passing directly to the coking zone.

A further salient object of the invention is to provide a method for more effectively controlling the cracking temperatures and coke or residue-forming temperatures in the respective cracking and coke or residue-forming zones.

A further object of the invention is to remove from the residual material before passing the same to the coke or residue-forming zone, constituents which lend themselves to cracking without forming substantial amounts of coke, with the result that the capacity of the operation is materially increased and at the same time low boiling products of the desired quality are produced.

Additional objects and advantages will be apparent from the more detailed description of the invention.

In accordance with the present invention a residuum from the initial fractionating zone or zones which may comprise the initial condensate from the cracked vapors or a mixture of such condensate and topped or stripped crude is first subjected to an additional distilling operation, preferably under reduced pressure, the residual material from the distilling operation being subsequently passed directly to the coking zone and the evolved vapors from the distillation treatment after being fractionated and condensed are given a preliminary heat treatment before passing to the coking zone.

In the preferred modification the evolved vapors from the distilling operation previously referred to are divided into a heavier and lighter fraction, the lighter fraction being combined with the recycle stock passing to the cracking zone and the heavier fraction subjected to a relatively milder heat treatment preferably in a tubular heating unit before passing to the coking or residue-forming zone.

For a better understanding of the invention reference is now made to the accompanying drawing which illustrates in a conventional manner a suitable apparatus for carrying out the present invention.

In the drawing the reference character 10 designates a furnace setting having suitable heating elements such as a burner 11 for maintaining the furnace at the desired temperature. Mounted in the hotter portion of the furnace is a tubular heating coil 12 having the ends of 55

the tubes interconnected to form a serpentine path for the passage of fluid therethrough. The inlet end 13 of the coil 12 is connected to a source of hydrocarbons to be subjected to cracking treatment such as, for example, a clean condensate stock of the gas-oil and/or the kerosene type from the fractionating zone.

The oil after passing through the heating coil 12, wherein it is subjected to pyrolytic conditions under relatively high superatmospheric pressure is conveyed through line 14 to a coking drum 15. As illustrated, the line 14 is provided with manifold outlet lines 16, 17 and 18 leading into the coking drum 15 and provided with valves 19, 20 and 21 respectively so that the hot products from the cracking coil 12 may selectively pass to the coking drum through any one or more of manifold lines as conditions may dictate.

Leading from the upper end of the coking drum 15 is a vapor line 22 for conducting vapors evolved in the coking drum 15 to a primary fractionating tower 23 provided with suitable fractionating elements 24 for cooling and fractionating the evolved vapors.

If desired fresh charging oil may be introduced into the primary fractionating tower through line 25 having manifold outlets 26 and 27 provided with valves 28 and 29 for selectively discharging the oil in to different vertical zones of the fractionating tower. As shown a preheating coil 30, mounted in the cooler or economizer section of the furnace setting 10, is interconnected with charging line 25 through lines 31 and 32 so that by properly regulating valves 33, 34 and 35 in lines 25, 31 and 32 respectively a portion or all of the charging oil may be preheated before passing to the fractionating tower 23. In lieu of providing preheating coil 30, other convenient sources of heat may be utilized for preheating the oil. The desirability of preheating the oil and the extent of such preheating will be determined largely by the character of the oil to be treated and the temperature conditions desired to be maintained within the fractionating tower 23.

The charging line 25 is provided with a pump 36 for subjecting the oil to sufficient pressure to discharge it against the pressure maintained within the fractionating tower 23 which, together with heating coil 12 and coking drum 15, is ordinarily maintained under relatively high superatmospheric pressure. The fresh oil in fractionating tower 23 coming in contact with the hot products from the coking drum 15 serves to cool the hot vapor products and in turn becomes heated so that the lighter constituents are vaporized leaving a topped or reduced crude residuum.

The fractionating tower 23 is connected to a vapor outlet line 37 leading to a secondary fractionating tower 38 provided with suitable fractionating elements 39 for further cooling and fractionating the vapors from the primary fractionating tower 23.

Uncondensed vapors from the secondary fractionating tower 38 are removed through vapor outlet line 40, conducted through a suitable condenser 41, wherein vapors having the desired end point for motor fuel are condensed, and thence passed to a collecting tank 42 having a gas outlet line 43 for removing the permanent and uncondensed gases and a liquid withdrawal line 44 for removing the desired fraction to suitable storage receptacles (not shown).

The condensate from the second fractionat-

ing tower 38, which ordinarily is of suitable composition for further cracking treatment in coil 12 is withdrawn from the tower and conducted to the cracking coil 12 through line 45 provided with oil pump 46 for applying the desired feed pressure to the oil passing through the cracking coil. If desired a portion or all of this condensate may be withdrawn from the system through line 47 and/or additional oil for cracking may be introduced into the system through line 48 provided with a pump 49.

The hot unvaporized constituents in the bottom of fractionating tower 23, which may comprise the heavier initial pressure condensate removed from the cracked products or a mixture of such condensate and topped or stripped residual products from the fresh charge injected through line 25, is withdrawn from the bottom of fractionating tower 23 through line 50 having a pressure-reducing valve 51 and the withdrawn oil is introduced into a stripping chamber 52 which is normally maintained at a pressure materially below that existing in the fractionating tower 23.

The reduction in pressure within the chamber 52 liberates, in vapor form, lighter constituents from the residual material. The upper zone of the stripping chamber 52 is provided with fractionating elements 53 for condensing all but the vapors having the desired end point.

As illustrated, I also prefer to separate a condensate from the vapors evolved in the stripping chamber and to this end the upper zone of the tower 52 is provided with an annular trough 54 forming a central vapor passage 55 having an angular deflecting plate 56 for diverting condensate formed in the upper zone into the annular trough.

The condensate collected in the pan 54 is ordinarily not sufficiently free from coke-forming constituents as to be entirely suitable for subjection to severe cracking temperatures within the cracking coil 12 and consequently I prefer to subject this condensate to a milder heat treatment in a separate tubular heating coil. Accordingly the condensate is withdrawn from the annular trough through line 57 provided with a pump 58 which forces the oil through heating coil 59 mounted in the furnace setting 10. The condensate, after passing through the heating coil 59, wherein it is subjected to a mild heat treatment, which may be just below, or in the range of incipient cracking or a substantial degree of cracking, preferably in the liquid phase, is discharged through line 60 into the transfer line leading from the cracking coil to the coking drum and in which it admixes with the cracked products from the coil 12. If desired the line 60 may discharge directly into the coking drum 15.

The uncondensed vapors from the stripping tower 52 are withdrawn through line 61 leading to a condenser 62 in which the desired constituents are condensed after which they are passed to a collecting tank 63 having a gas outlet 64 and a liquid withdrawal line 65 provided with a valve 66.

The liquid withdrawn from collecting tank 63 is ordinarily suitable for cracking treatment and may consequently be introduced into line 45 leading to the cracking coil 12. If desired, however, all or part of this fraction may be withdrawn from the system through line 67 and subjected to further treatment such as a reforming treatment or all or part of it may be introduced through line 68 into the line 57 leading to the heating coil 59. As shown suitable valves are 75

provided for selectively transferring the oil to any of the three places just referred to.

It is sometimes desirable to operate the chamber 52 under sub-atmospheric pressure, in which case conventional operating means may be employed in line 61 or in connection with drum 63 to maintain the required degree of vacuum. Under these circumstances it may be advantageous to condense substantially all of the evolved vapors in the upper fractionating section of vessel 52, providing an additional drawoff pan for the lighter condensate above the pan 54, this lighter condensate being returned to line 45 leading to crack-coil 12, while that from the lower pan 54 is handled through heating coil 59 as previously described. The vapors leaving through line 61 may be condensed by direct contact with cooled condensate from the base of fractionator 38 and the composite subsequently passed to one or the other of the towers for reflux cooling.

Instead of depending upon the reduction in pressure to effect distillation of the bottoms passed from the primary tower 23 to the distilling or stripping tower 52, the lower end of the tower 52 may be heated by suitable means and/or steam or other suitable gas may be introduced thereinto to effect the desired distillation or stripping of the said bottoms.

The residual material from the bottom of the stripping tower 52 is withdrawn through line 69 having an oil pump 70 for forcing the oil into the coking drum through line 71 having manifold discharge outlets 72, 73 and 74 so that the residual material may be introduced into the coking drum at any one or more vertical zones in the drum.

The point of introduction of the various materials into the coking drum will depend largely upon the conditions desired to be maintained within the drum which in turn will be determined principally by the end products desired. For example it has been found that priming; that is to say, the carrying over of entrained coke and pitch into the vapor lines, can be largely avoided by properly distributing the point of introduction of the oil streams into the coking drum.

Better results are ordinarily secured, however, by passing the residual materials from pump 70 into the combined discharge line 80 from the two sections of the heater, through line 81 to commingle with these hotter oils before entering the coking drum.

The coking drum 15 is shown provided with a bottom manway 75 for the purpose of coke removal when running to coke and a well 76 is shown adapted to contain suitable coke boring apparatus. When running to a semi-solid residuum such as pitch, the hot residue while still in liquid form may be withdrawn through line 77. In the latter case the resulting pitch will solidify upon cooling and may be pulverized for use as powdered fuel or otherwise utilized.

When running to coke it is preferable to provide a plurality of coking drums 15 arranged in parallel so that any one or more of the drums may be disconnected from the remainder of the unit without interrupting operation of the unit and the coke removed from the disconnected drum after which the cleaned drum may be placed back in service and another drum or drums disconnected and cleaned in a like manner. If desired the line 45 leading to the cracking coil 12 and the line 57 leading to the heating coil 59 may be interconnected by a line 78 provided with a valve 79 so that in event an insufficient supply of condensate from the stripping tower 52 is avail-

able a portion of the oil from line 45 may be passed through heating coil 59 and thus prevent overheating of the tubes.

By treating the residual material from the bottom of the primary fractionating tower in the manner hereinbefore described, wherein the lighter constituents are removed prior to passing the same to the coking drum and wherein a desired fraction of the residual material from the fractionating tower is given a preliminary independent heat treatment before being passed to the coking drum, makes it possible to maintain temperature conditions in the cracking zone conducive to the most effective conversion of the products without regard to the temperature conditions desired to be maintained in the coking drum and, conversely, the coke drum may be maintained under desired temperature conditions conducive to most effectively convert the contents of the coke drum to the desired end products without adversely affecting the temperature conditions desired to be maintained in the cracking zone.

For a better understanding of the invention the following more specific example, of temperature and pressure conditions suitable for carrying out the method, may be helpful, it being understood that the invention is not limited or dependent upon specific conditions here mentioned and that the conditions of temperature and pressure may vary widely without effecting, or departing from, the invention.

For purposes of illustration the cracking stock, which may be of any suitable type which will lend itself to cracking conditions without forming substantial amounts of coke such as, for example, a clean condensate stock of the gas oil or kerosene type, and which may be composed partially or entirely of reflux condensate from the fractionating tower 38, may be heated to a temperature ranging from 800 to 1000° F. while passing through the cracking coil 12 during which time it may be subjected to an outlet pressure ranging, for example, between 200 and 750 pounds per square inch. The cracked products, from coil 12, introduced into the coking drum 15 and coming into contact with the residual and fractionated products from the stripping chamber 52 may be permitted to come to an equilibrium temperature ranging from 750 to 900° F. The coke drum and the connecting fractionating towers 23 and 38 may be maintained under substantially uniform pressures, except for frictional losses, or the respective chambers may be maintained under differential pressure if desired. Under the usual conditions of operations it is ordinarily desirable to maintain these pressures in excess of 100 pounds per square inch in order that pressure of the gas at the outlet of the receiver 42 may be sufficiently high to be introduced into the gas lines. The pressures in these chambers may, however, be maintained considerably in excess of 100 pounds if desired and may be of the order of 400 or 500 pounds or even more.

The vapors, from the coking drum, introduced into the fractionating chamber 23, may be at a temperature approximating 750 to 900° F. and the uncondensed vapors in fractionating tower 23 may be cooled to a temperature ranging from 650 to 750° F. before being introduced into the second fractionating tower 38. The vapors in fractionating tower 38 are cooled sufficiently to produce the desired end product such as, for example, in the neighborhood of 300° F.

The residual products from fractionating tower 23 may be introduced into the stripping chamber 52 at a temperature ranging from 700 to 800° F. as hereinbefore described the pressure conditions 5 within the stripping zone will depend upon the kind and extent of stripping action desired. In cases where the stripping is to be effected by reduction in pressure the pressure will be materially lower than that existing in fractionating 10 chamber 23 and may, for example, be at a pressure below 25 pounds per square inch down to pressure approaching a vacuum. In cases where it is desired to effect the stripping action partially or entirely by additional heat or by steam 15 the pressure may be maintained at or below the pressure maintained in the fractionating chamber 23 such as, for example, from 50 to 100 or more pounds. The condensate from the stripping zone passing through coil 59 may be heated 20 to a temperature ranging from 600 to 800° F., for example, so that the oil will be brought to a temperature below cracking if desired or substantial cracking may be effected as desired.

The residual products from the stripping tower 25 52 may be introduced directly into coking drum 15 at a temperature approximating from 600 to 700° F. and the condensate from tower 30 38 may be introduced to the inlet of the cracking coil 12 at a temperature approximating from 550° F. to 650° F.

In cases where it is desired to introduce fresh oil such as raw or reduced crude, for example, into the fractionating tower 23 the oil may be preheated by passing through coil 30 to a temperature approximating from 300 to 500° F. or it 35 may be passed to the fractionating tower without previous preheating.

While the preferred embodiment of the invention 40 has been described, and a specific example given for illustrative purposes, it is understood that the invention embraces such modifications and variations as come within the scope and spirit thereof and that the invention is not to be limited except as necessary to distinguish from 45 prior art.

What I claim is:

1. In the treatment of hydrocarbon oils, where- 50 in the oil is converted into ultimate products consisting principally of a motor fuel and a solid or semi-solid residue, the process which comprises heating an oil containing higher boiling hydrocarbons to a temperature and for a period of time sufficient to convert higher boiling hydrocarbons into lower boiling ones, while maintaining said hydrocarbons under a pressure materially above atmospheric, fractionating vapors evolved during said conversion treatment in a plurality of independent fractionating zones, contacting the hot products from said conversion treatment with 55 fresh oil in the first of said fractionating zones to thereby heat said oil and vaporize lighter constituents therefrom, distilling residual products from said first fractionating zone under a pressure materially lower than that existing in said 60 first fractionating zone to thereby vaporize lighter constituents therefrom, passing the residual products from said distillation to a residue-forming zone, heating the distillate resulting from said distillation, passing the heated distil- 65 late and products undergoing conversion into said residue-forming zone in direct contact with the residue products resulting from said distillation, whereby heat from said distillate and products undergoing conversion is utilized to form an 70 ultimate product substantially solid at normal 75

room temperatures, withdrawing vapors from another of said fractionating zones and condensing a desired gasoline fraction therefrom.

2. In the treatment of hydrocarbon oils, where- 5 in the oil is converted into ultimate products consisting principally of a motor fuel and a solid or semi-solid residue, the process which comprises heating an oil containing higher boiling hydrocarbons to a temperature and for a period of time sufficient to convert higher boiling hydrocarbons into lower boiling ones, while maintaining said hydrocarbons under a pressure materially above atmospheric, fractionating vapors evolved during said conversion treatment in a plurality of independent fractionating zones, contacting 10 the hot products from said conversion treatment with fresh oil in the first of said fractionating zones to thereby heat said oil and vaporize lighter constituents therefrom, distilling residual products from said first fractionating zone to thereby 15 vaporize lighter constituents therefrom, passing the residual products from said distillation to a residue-forming zone, heating distillate resulting from said distillation, passing the heated 20 distillate and products undergoing conversion 25 into said residue-forming zone in direct contact with the residue products resulting from said distillation, whereby heat from said distillate and products undergoing conversion is utilized to form an ultimate product substantially solid at 30 normal room temperatures, withdrawing vapors from another of said fractionating zones and condensing a desired gasoline fraction therefrom.

3. In the treatment of hydrocarbon oils where- 35 in the oil is converted into ultimate products consisting principally of a motor fuel and a solid or semi-solid residue, the process which comprises heating an oil containing higher boiling hydrocarbons to a temperature and for a period of time sufficient to convert higher boiling hydrocarbons into lower boiling hydrocarbons while maintaining said hydrocarbons under a pressure materially above atmospheric, fractionating vapors resulting from said conversion treatment in a plurality of independent fractionating zones, 40 distilling heavier condensate from the first of said fractionating zones under a pressure materially lower than that existing in said first fractionating zone to thereby vaporize lighter constituents therefrom, fractionating said lighter constituents to form a lighter and heavier fraction, subjecting said lighter fraction to conversion treatment, separately heating said heavier fraction and passing said heavier fraction into a residue-forming zone, passing products undergoing conversion into said residue forming zone, 45 passing residual products resulting from said distillation to said residue-forming zone in direct contact with products introduced thereto to thereby utilize the heat of said products to form 50 an ultimate product which is substantially solid at normal room temperature, withdrawing vapors from the last of said fractionating zones and condensing a desired gasoline fraction therefrom.

4. In the treatment of hydrocarbon oils where- 55 in the oil is converted into ultimate products consisting chiefly of motor fuel and a solid or semi-solid residue, the process which comprises heating an oil containing higher boiling hydrocarbons to a temperature and for a period sufficient 60 to convert higher boiling hydrocarbons into lower boiling ones while maintaining said hydrocarbons under a pressure materially above atmospheric, fractionating vapors resulting from said conversion treatment in a plurality of independent frac- 65 70 75

tionating zones, contacting the hot products from said conversion treatment from fresh oil in the first of said fractionating zones to thereby heat said oil and vaporize lighter constituents therefrom, distilling residual products from said first fractionating zone under a pressure materially lower than that existing in said fractionating zone to thereby vaporize lighter constituents therefrom, fractionating the evolved vapors resulting from said distillation and separating a lighter and heavier fraction from said distilled vapors, subjecting said lighter fraction to said conversion treatment, separately heating said heavier fraction, passing said heated heavier fraction to a residue-forming zone, passing products undergoing conversion to said residue forming zone, contacting residual products resulting from said distillation with products introduced into said residue-forming zone to thereby utilize heat from said products in forming an ultimate product substantially solid at normal room temperature, removing vapors from the last of said fractionating zone and condensing a desired gasoline fraction therefrom.

25. 5. In the treatment of hydrocarbon oils wherein the hydrocarbons are converted into ultimate products comprised principally of gasoline and a residual product substantially solid at normal temperatures which comprises subjecting hydrocarbon oils containing hydrocarbons boiling above the normal gasoline range to pyrolytic treatment at relatively high superatmospheric pressure to convert higher boiling hydrocarbons into lower boiling hydrocarbons, fractionating vapors resulting from said pyrolytic treatment at relatively high pressure to separately form heavy and light condensate fractions, removing vapors from the fractionating zone and condensing a desired fraction therefrom, subjecting said light condensate fraction to said pyrolytic treatment, subjecting the heavier condensate fraction to distillation under pressure materially reduced from that maintained during fractionation to vaporize lighter constituents thereof, fractionating said last mentioned vapors to form a resulting condensate, separately heating said resulting condensate, and commingling the residual material resulting from said distillation, said last named heated condensate and the products resulting from said first mentioned pyrolytic treatment in an enlarged zone to thereby convert residual material into a product substantially solid at normal temperatures.

6. In the art of converting higher boiling hydrocarbon oils into lower boiling ones wherein oil is heated to a cracking temperature under superatmospheric pressure and thereafter passed to an enlarged zone wherein vaporous and residual constituents of the heated oil are separated, the vaporous constituents being thereafter subjected to fractionation in a plurality of fractionating zones, and fresh charging oil introduced into the first of said fractionating zones, the improvement that comprises distilling residual products of said fresh oil and condensate from the first of said fractionating zones at lower pressure than that obtaining in the first fractionating zone to thereby vaporize lighter constituents therefrom, passing residual products resulting from said distillation directly to said enlarged zone wherein vaporous and residual constituents are separated, recovering a condensate from said vaporized lighter constituents, heating said condensate to an elevated temperature separately from said oil heated to a cracking temperature and passing the thus heated

condensate to said enlarged zone wherein vaporous and residual constituents are separated.

7. In the art of converting higher boiling hydrocarbon oils into lower boiling ones wherein oil is heated to a cracking temperature under superatmospheric pressure and thereafter passed to an enlarged zone wherein vaporous and residual constituents of the heated oil are separated, the vaporous constituents being thereafter subjected to fractionation in a plurality of fractionating zones, and fresh charging oil introduced into the first of said fractionating zones, the improvement that comprises distilling residual products of said fresh oil and condensate from the first of said fractionating zones at lower pressure than that obtaining in the first fractionating zone to thereby vaporize lighter constituents therefrom, passing residual products resulting from said distillation directly to said enlarged zone wherein vaporous and residual constituents are separated and withdrawing condensate from a subsequent one of said fractionating zones and passing the same to said cracking operation as distillate charging stock therefor.

8. The method of converting hydrocarbon oils into lighter and heavier products which comprises subjecting a stream of distillate charging stock to cracking and discharging the stream of cracked products into an enlarged conversion chamber, separately withdrawing vapors from said conversion chamber and passing them through a plurality of fractionating zones arranged in series, introducing heavy charging oil into the first of said series of fractionating zones whereby said charging oil intimately contacts the vapors therein and light constituents are distilled therefrom, separately withdrawing from said first fractionating zone residues of said charging oil and passing the same to an independent distilling zone wherein vaporizable constituents are distilled therefrom, forming a condensate from the latter distilled constituents and heating said condensate to a high temperature while flowing it in an independent restricted stream, thereafter discharging the stream of heated condensate into said conversion chamber, separately withdrawing from said independent distilling zone unvaporized residue and passing the same into said enlarged conversion chamber wherein it is additionally distilled and converted by contact with the aforementioned streams of highly heated products discharged thereinto, and withdrawing reflux condensate from a subsequent one of said series of fractionating zones and passing the same to said cracking operation as distillate charging stock therefor.

9. In a method of processing hydrocarbon oil wherein a clean condensate stock is passed through a heating coil and raised to a cracking temperature while under superatmospheric pressure adequate to form a substantially solid residue by the heat imparted to said stock during its passage through the heating coil, the products from the heating coil transferred to an enlarged coking zone wherein residue is converted to coke by the contained heat thereof and the vapors liberated within the coking zone separately withdrawn therefrom; the improvement which comprises fractionally condensing said vapors in a fractionating zone in contact with fresh oil containing constituents unvaporizable under conditions there obtaining to condense at least part of the insufficiently cracked vapors as reflux condensate, separately condensing sufficiently cracked vapors and separately collecting the same as a product of the

process, withdrawing a mixture of unvaporized fresh oil and reflux condensate from said fractionating zone, subjecting said mixture to distillation at a lower pressure than that obtaining in said fractionating zone to vaporize a lower-boiling fraction therefrom, fractionating said vapors to

form a condensate, heating said condensate to a cracking temperature, thereafter discharging the products thus heated into said coking zone and passing residual constituents resulting from said distillation directly to said enlarged coking zone. 5

GEORGE ARMISTEAD, JR.
